US00D874433S

(12) **United States Design Patent** (10) **Patent No.:** **US D874,433 S**
Boerner (45) **Date of Patent:** **** Feb. 4, 2020**

(54) **SPEAKER**

(71) Applicant: **YAMAHA CORPORATION**,
 Hamamatsu-shi (JP)

(72) Inventor: **Marco Boerner**, Hamamatsu (JP)

(73) Assignee: **YAMAHA CORPORATION**,
 Hamamatsu-shi, Shizuoka (JP)

(**) Term: **15 Years**

(21) Appl. No.: **29/654,475**

(22) Filed: **Jun. 25, 2018**

(30) **Foreign Application Priority Data**

Dec. 26, 2017 (JP) 2017-029146

(51) **LOC (12) Cl.** **14-01**

(52) **U.S. Cl.**
 USPC **D14/214**

(58) **Field of Classification Search**

(57) **CLAIM**

The ornamental design for a speaker, as shown and described.

DESCRIPTION

FIG. 1 is a perspective view of the front, top and right side of a speaker showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the speaker is included for the purpose of illustrating portions of the speaker and forms no part of the claimed design.

1 Claim, 3 Drawing Sheets
